DESIGN FOR A CLIP BROOCH OR THE LIKE

Harold Graeter, Blairstown, N. J., assignor to Cartier, Inc., New York, N. Y., a corporation of
New York

Application October 18, 1946, Serial No. 134,022

Term of patent 14 years

(Cl. D45—19)

To all whom it may concern:

Be it known that I, Harold Graeter, a citizen of the United States of America, residing at Blairstown, in the county of Warren and State of New Jersey, have invented a new, original, and ornamental Design for a Clip Brooch or the like, of which the following is a specification, reference being had to the accompanying drawing, forming part thereof.

Fig. 1 is a front elevation of a clip brooch, showing by new design.

Fig. 2 is a side elevation of the clip brooch.

Fig. 3 is an elevational view of the back of the clip brooch.

I claim:

The ornamental design for a clip brooch or the like, as shown.

HAROLD GRAETER.
